UNITED STATES PATENT OFFICE.

THOMAS LUCIEN TALIAFERRO, OF CHICAGO, ILLINOIS.

BOTTLE-CAP AND METHOD OF SEALING BOTTLES.

1,381,365.

Specification of Letters Patent. Patented June 14, 1921.

Application filed July 8, 1920. Serial No. 394,634.

To all whom it may concern:

Be it known that I, THOMAS L. TALIAFERRO, a citizen of the United States, residing at Chicago, in the county of Cook, State 5 of Illinois, have invented certain new and useful Improvements in Bottle-Caps and Methods of Sealing Bottles, of which the following is a description, reference being had to the accompanying drawing and to the 10 figures of reference marked thereon.

The invention relates to new and useful improvements in bottle caps, and the process of sealing bottles.

An object of the invention is to provide a 15 bottle cap which is so constructed that the sealing material within the bottle cap may be reshaped while softened by heat for the purpose of insuring a perfect seal.

A further object of the invention is to 20 provide a bottle cap of the above character wherein the metal part of the top is so constructed that it may be reshaped for the purpose of pressing the sealing material while softened by heat into more intimate sealing 25 contact with the parts of the bottle cap and the adjacent parts of the bottle.

A still further object of the invention is to provide a process of sealing bottles wherein 30 the sealing material is reshaped and brought into more perfect sealing with the bottle and the cap after the cap has been placed on the bottle.

In the drawings—

Figure 1 is a sectional view through the 35 bottle neck having my improved bottle cap applied thereto;

Fig. 2 is a similar view, but showing the 40 cap as having been reshaped for forcing the sealing material while softened by heat into intimate sealing contact between the parts of the cap and the bottle, and

Fig. 3 is a view similar to Fig. 1 but showing a slightly modified form of sealing gasket.

The bottle cap is preferably formed of 45 metal and is provided with a central top portion and a depending flange provided with screw threads or other securing devices, whereby the bottle cap may be firmly secured 50 to the neck of the bottle and drawn down on to the neck of the bottle. Placed between the inner surface of the top of the cap and the neck of the bottle is a sealing gasket formed preferably of a plastic rubber composition 55 which is capable of softening so that it may be reshaped when subjected to heat of a relatively low temperature and which retains the shape in which it is molded or formed. After the cap has been screwed on to the bottle neck and the sealing material or gasket clamped against the seat on the bottle, the cap is then subject to reshaping. This is preferably accomplished by forming the top with a bulged portion normally bulged outwardly, which upon pressure, may be caused to bend inwardly and force the sealing material more intimately into contact with the parts of the cap and the bottle.

Referring more in detail to the drawings, 70 my improved construction of cap will be better understood and the method of sealing bottles will be described more in detail. In Fig. 1 of the drawings, I have shown a portion of a bottle indicated at 1. The bottle 75 neck is formed with a thread 2. My improved cap consists of a top portion 3 and a depending flange 4 which is preferably threaded as indicated at 5 so as to engage the threads 2 on the neck of the bottle for se- 80 curing the cap to the bottle. The lower edge of the cap is reinforced by curling as indicated at 6. The top and the flange as shown in the drawings, consist of two separate pieces of metal joined by a seam as at 7. So 85 far as this part of the construction of the cap is concerned, it may be otherwise formed. As a matter of fact, the cap may be formed of a single piece of metal if desired. The top portion 3 is formed with a central out- 90 wardly bulged or bent portion 3^a. Located within the cap is a sealing gasket 8 which as shown in Figs. 1 and 2, is in the form of a disk. This sealing gasket is preferably formed of non-vulcanized rubber and is 95 plastic and capable of being reshaped when heated to a relatively low temperature and retained in the shape in which it is molded when cooled. In other words, the gasket is not an elastic article capable of spring- 100 ing back after being released from pressure. The cap is placed on the bottle and the gasket clamped against the seat at the extreme edge of the bottle neck, after which the contents of the bottle is heated for sterilizing, 105 or if the contents placed in bottle is hot, the heat incident thereto will soften the gasket 8. If the contents is not hot, this gasket may be softened by applying heat to the bottle cap. The essential point is that 110 the gasket shall be softened by heating after the cap is placed on the bottle neck. While

the gasket is softened through the heat applied thereto, the outwardly bulged portion 3^a is forced by pressure inwardly as indicated in Fig. 2. This inward bending of the 5 metal will force the gasket outwardly against the flange 2 of the bottle cap and will also force the gasket material more intimately into contact both with the seat 9 at the extreme outer end of the bottle neck 10 and the parts of the cap adjacent thereto. When the gasket cools, it retains its shape, and the sealing of the bottle is insured.

In Fig. 3 of the drawings, I have shown a sealing gasket as indicated at 10 in the 15 form of a ring, otherwise the cap and gasket are similar in construction to that shown in Figs. 1 and 2.

My improved process of sealing bottles consists in the applying of the screw cap 20 having the plastic gasket therein to the bottle, and then subjecting the gasket to heat to soften the same, after which the metal is reshaped to force the gasket material into more intimate contact with the extreme end 25 of the bottle neck and the adjacent parts of the cap to form a more perfect seal. The bottle and cap are then permitted to cool and the gasket will remain in this reshaped condition, effecting a perfect seal of the bottle.

30 It is obvious that the construction of the cap may be changed from that shown in the drawings, also that other ways of reshaping the cap may be devised, the essential features consisting in the use of a gasket 35 which softens at low temperature and a cap which may be reshaped to bring about a reforming of the gasket in place on the bottle and between the neck of the bottle and the cap, which reforming causes the gasket to 40 make more intimate contact with the associated parts of the cap and the bottle, and thus form a seam.

Having thus described the invention, what I claim as new and desire to secure by Letters-Patent, is—

45 1. A bottle cap consisting of a top portion and a depending flange, a plastic gasket located in said cap adjacent said top portion and adapted to soften by heat at a relatively low temperature whereby said gasket may be reshaped through a bending of the metal 50 of the cap, said cap being so constructed whereby the same may be reshaped so as to force the gasket when softened into more intimate sealing contact with the bottle and 55 the cap after said cap is placed on the bottle.

2. A bottle cap consisting of a top portion, a depending threaded flange, said top portion having an outwardly bulged central section adapted to be bent inwardly after 60 the cap is placed on the bottle, and a plastic sealing gasket adapted to soften by heat at a relatively low temperature located in said cap and adapted to be pressed by said cap against the neck of the bottle, said gasket 65 being so disposed that the inward bending of the bulged portion of the top of the cap will force the sealing gasket into more intimate contact with the bottle cap and the neck of the bottle.

70 3. A process of sealing bottles consisting in securing thereto a bottle cap having a gasket of plastic sealing material disposed between the top of the cap and the mouth of the bottle, which gasket is adapted to soften 75 by heat at a relatively low temperature and reshaping the bottle cap after it is attached to the bottle and while said sealing material is softened by heat for causing said sealing material to make more intimate contact with 80 said cap and bottle.

In testimony whereof I affix my signature.

THOMAS LUCIEN TALIAFERRO.
